UNITED STATES PATENT OFFICE.

JAMES W. SNEDEKER, OF ADRIAN, MICHIGAN.

TOOL HOLDER.

Application filed May 31, 1921. Serial No. 474,004.

To all whom it may concern:

Be it known that I, JAMES W. SNEDEKER, a citizen of the United States, and residing at Adrian, in the county of Lenawee and 5 State of Michigan, have invented a new and Improved Tool Holder, of which the following is a specification.

This invention relates to receptacles for tools and other small articles, and its object 10 is to produce a device of this character formed of a series of compartments which may be opened to present its entire contents for full inspection, which can be collapsed to small dimensions, which consists of a 15 number of compartments in which the tools may be separately held, and which may be made of fibrous material so that the tools will be fully protected from injury.

This invention consists of a receptacle 20 comprising a series of parallel rods in two substantially parallel planes, the rods in one plane being midway the rods in the other, a sheet of fabric extending back and forth around the rods of the two planes so as to 25 form a series of compartments of triangular cross section, means to attach the fabric to the rods, and strips of fabric at the ends of the rods to close the ends of the compartments.

It also consists in a series of metal links 30 mounted on the ends of the rods to hold them in proper position, the links being in two series, each series extending from the rods of one plane to the rods of the other 35 parallel to each other.

It also consists in split sheet metal cylinders fitting around the fabric and the rods to secure them together.

It also consists in the details of construction 40 illustrated in the accompanying drawing and particularly pointed out in the claims.

In the drawing, Fig. 1 is a perspective view of this improved tool holder when 45 opened. Fig. 2 is an end view thereof when folded. Fig. 3 is a central longitudinal section of one end thereof. Fig. 4 is an elevation of one end of a side thereof.

Similar reference characters refer to like 50 parts throughout the several views.

A strip 1 of fabric whose width is that of the desired holder is passed over the upper rods 2 and under the lower rods 3 which are all parallel to each other in two sets in the 55 finished device. I prefer to fit trough shaped strips of sheet metal 4 over the fabric at

these rods and bend the strips to cylindrical form to lock the fabric to the rod, as shown in Fig. 3, but it is evident that the locking strips may be omitted from some of the 60 rods and that they may be of any desired length.

Strips 5 and 6 of fabric, preferably being provided with metal eyelets 7, are then slipped over the ends of the rods and the 65 ends 8 of these strips are secured to the end folds of the strip 1 in any desired manner, metal fasteners 9 being shown. Links 10 and 11 are then slipped over the ends of the rods, these ends being slightly headed outside the links to prevent removal. These 70 links may be omitted if a stiff fabric 1 is used. If desired, a flexible flap 12 may extend from one end fastening strip 4 and may be wound around the collapsed holder, 75 as shown in Fig. 2, tapes 13 being provided to hold the receptacle collapsed if desired.

As the walls of each compartment are of fabric, this holder is admirably adapted 80 for fine tools and other articles such as silverware which should be kept separated to prevent injury. When opened out as shown in Fig. 1, each article in each compartment is fully displayed, is readily accessible and can be returned to its compartment with minimum effort. This makes 85 this holder especially adapted for traveling salesmen's samples and for the tools used on automobiles.

The details of construction and the proportions of the parts may all be changed by those skilled in the art without departing 90 from the spirit of my invention as set forth, in the following claims.

I claim:

1. A collapsible receptacle comprising a series of parallel rods in two planes, a sheet of fabric extending back and forth between the rods of the two planes to form a series 100 of compartments, and means for holding the rods of the two planes spaced apart.

2. A collapsible receptacle comprising a series of parallel rods in one plane, a sheet of fabric connected to said rods and forming a series of compartments between the rods, and pairs of links at both ends of said rods, each link being pivoted at one end to one of said rods and at its other end to the end of a link attached to the next adjacent rod.

3. A collapsible receptacle comprising a series of parallel rods in two substantially 110

parallel planes, the rods of each plane being spaced midway the rods of the other, a sheet of fabric extending back and forth around the rods of the two planes to form a series 5 of compartments triangular in cross section, means to attach the fabric to the rods, and strips of fabric closing the ends of the compartments.

4. A collapsible receptacle comprising a 10 series of parallel rods in two substantially parallel planes, the rods of each plane being spaced midway the rods of the other, a sheet of fabric extending back and forth around the rods of the two planes to form a series 15 of compartments triangular in cross section, means to attach the fabric to the rods, strips of fabric closing the ends of the compartments, said strips having perforations so 20 said rods may extend through the strips, and links connecting the upper rods and the lower rod of each compartment.

5. A collapsible receptacle comprising a series of parallel rods in two substantially parallel planes, the rods of each plane being 25 spaced midway the rods of the other, a sheet of fabric extending back and forth around the rods of the two planes to form a series of compartments triangular in cross section, means to attach the fabric to the rods, and 30 strips of fabric closing the ends of the compartments, said attaching means comprising trough-shaped strips of metal bent to cylindrical form around the fabric and rods.

6. A collapsible receptacle comprising a 35 series of parallel rods in two substantially parallel planes, the rods of each plane being spaced midway the rods of the other, a sheet of fabric extending back and forth around the rods of the two planes to form a series of 40 compartments triangular in cross section, means to attach the fabric to the rods, strips of fabric closing the ends of the compartments, said strips having perforations so 45 said rods may extend through the strips, and a series of metal links mounted on the ends of the rods to hold them in position, the links

being in two series, each series extending from the rods of one plane to the rods of the other and parallel to each other, all the links being of the same length.

7. A collapsible receptacle comprising a series of parallel rods in two substantially parallel planes, the rods of each plane being spaced midway the rods of the other, a sheet of fabric extending back and forth around the rods of the two planes to form a series of compartments triangular in cross section, means to attach the fabric to the rods, strips of fabric closing the ends of the compartments, said attaching means comprising trough-shaped strips of metal bent to cylindrical form around the fabric and rods, and a flap of flexible material extending from one end fastening strip and adapted to be wound around the receptacle when collapsed.

8. A collapsible receptacle comprising a series of parallel rods in two substantially parallel planes, a sheet of fabric extending back and forth around the rods of the two planes to form a series of compartments, means to attach the fabric to the rods, and a strip of fabric closing the ends of the compartments.

9. A collapsible receptacle comprising a series of parallel rods in two substantially parallel planes, a sheet extending back and forth around the rods of the two planes to form a series of compartments, means to attach the fabric to the rods of one plane, and means to close the ends of the compartments.

10. A collapsible receptacle comprising a series of parallel rods in two substantially parallel planes, a sheet extending back and forth around the rods of the two planes to form a series of compartments, means to attach the fabric to the rods of one plane, means to close the ends of the compartments, and means connecting the ends of each of the rods of one plane to the ends of two rods of the other plane.

JAMES W. SNEDEKER.
